CLAYTON O. KAUFFMAN, OF SANTA ANA, CALIFORNIA

APPARATUS FOR PRODUCING TREMOLO EFFECTS

Application filed August 19, 1929. Serial No. 386,855.

This invention relates to a device or apparatus adapted for use on various stringed instruments where it is desired to produce a tremolo effect or a vibration resulting in a tremolo effect.

More particularly, the invention relates to a movable tail-piece for stringed instruments, whereby the pitch of the sounds produced by the vibrating strings may be varied so as to produce a tremolo effect.

The invention will hereinafter be described with particular reference to the application of the device of this invention to a portable stringed instrument, such as for example, a banjo. It is to be understood, however, that the invention is not limited in its application to a portable stringed instrument, but relates to the production of tremolo effects on all stringed instruments, such as for example, mandolins, guitars, banjos, harps or pianos.

Tremolo devices have been constructed for use with certain stringed instruments, but such tremolo devices have had two major faults. In the first place, they could not be easily operated. Most stringed instruments are operated by plucking the strings with a movement of the hand at right angles to the axis of the strings. The tremolo devices of the prior art had to be operated by a movement of the hand at right angles to the movement executed during playing. Furthermore, the tremolo effect which was produced varied the pitch of the note or sound being emitted by the instrument, such variation changing the average pitch to above the normal or desired pitch or tone. For example, if the note "a" was sounded on a string, the tremolo would cause the pitch to vary between "a" and "b" giving an average of effective note equivalent to about "a" sharp.

An object of this invention is to disclose and provide a means for producing tremolo effects so that the effective frequency or pitch of a desired note is maintained substantially constant.

A still further object is to disclose and provide means for alternately increasing and decreasing the tension in a vibrating string so as to vary the frequency of the vibration from above to below the normal frequency.

A still further object is to disclose and provide an apparatus by means of which tremolo effects can be obtained on stringed instruments.

Another object of this invention is to disclose and provide a device for varying the frequency of vibrations of stringed instruments to above and below normal or desired frequencies, so as to produce tremolo effects.

Other objects, uses and advantages of this invention as well as its novel characteristics and distinguishing features will become apparent from the following detailed description, reference being had to the appended drawings, in which:

Fig. 1 is a plan view of a banjo equipped with a device embraced by this invention.

Fig. 2 is an end view of the banjo showing in more detail the construction of the device.

Fig. 3 is a vertical section, taken along line 3—3 of Fig. 2.

Fig. 4 is a plan view, partly in section, of the device shown in Fig. 2, the section being taken along line 4—4 thereof.

Fig. 5 is a plan view, partly in section, of a modified form of device.

Fig. 6 is a vertical section taken along line 6—6 of Fig. 5.

As has been stated before, the invention will be described as it may be used and applied to a portable stringed instrument, and particularly to a banjo.

The various strings of the banjo, said strings being designated at 1, are preferably attached to a tail-piece 2 in any desired manner, the tail piece, for example, including a plurality of apertures 3 adapted to receive the knotted ends of the strings 1. The strings 1 then preferably pass over a bridge 4 resting on the head 5 of the instrument. Well known means for attaching the head to the rim 6 of the instrument may be employed. Preferably, the bridge 4 is provided with a slightly curved base 7. The tail-piece 2 is preferably attached to a stationary member 8 through the intervention of suitable elastic spring means.

As shown in Figs. 2, 3 and 4, the stationary member 8 may be angular in section and provided with an outwardly extending lug 9.

adapted to receive a screw 10 having a threaded end provided with a nut 11, said screw 10 passing through a suitable lug 12 attached to the rim 6 of the musical instrument. The stationary member 8 is also preferably provided with an extension 13 having bifurcated ends 14 and 15. The movable tail-piece 2 is preferably connected to the stationary member 13 by means of an elastic means, such as 10 a tension spring 16, one end of said spring being connected to the stationary member 8 (at portion 13 thereof) as by means of a rivet or bolt 17.

If desired, a strap 18 may be employed for 15 gripping the end of the spring 16 and retaining it in vibrationless contact with the portion 13 of the stationary member 8, the strap 18 being attached to the member 13 by means of bolts or rivets 19. The opposed end of 20 the tension spring 16 may be connected by suitable means, as for example, the hooks 20 and 21, with the tail-piece 2. In this manner the strings 1 are maintained in tension by reason of the spring 16, minor adjustments of tension being made in the customary 25 manner by pegs 22 at the head of the instrument.

In order to create a quavering, tremulous or vibrating tone, means is provided for moving the tail-piece 2 so as to alternately increase or decrease the tension of the vibrating strings 1, while they are plucked or otherwise caused to vibrate. Such means may include a member 23 preferably consisting of 30 a heavy spring to which the hooks 20 and 21 are attached in any suitable manner, as for example, by welding. The member 23 has preferably one end firmly anchored as by means of the machine screw 24, to a block 40 or other solid portion 25 attached or made a part of the stationary member 8. The block 25 may be attached by means of machine screws 26 to the end 14 of portion 13 of the stationary member 8, the screws 26 operating in 45 slots 27 formed in the member 25 so as to permit an adjustment of the block 25 longitudinally.

The opposed end of the member 23 may be connected to a holder 28 adapted to receive 50 an actuating arm 29, said actuating arm 29 being preferably provided with a ring 30 adapted to receive one of the fingers of the person playing the instrument. A set screw 31 may be provided for adjustably positioning the actuating member 29 in the holder 28.

In order to increase the tension on the head 5 of the instrument, a lever arm 32 may be provided, said arm 32 being connected to the stationary member 8 by means of a screw 60 33 suitably attached to the member 8 as by welding, the screw 33 passing through an aperture in the member 32.

A nut 34 may be provided for attaching the member 32 to the member 8. A thumb screw 65 35 may be threadedly mounted in the member

32 and adapted to rest against the lower portion of member 8, so as to cause the opposite end 36 of the member 32 to bear down against the tail piece 2. The end 36 of member 32 may be provided with a plurality of grooves 70 37 extending transversely to the strings 1, said grooves 37 being adapted to receive a spacing plate 38 adapted to rest against the tail-piece 2. This construction permits any desired pressure to be applied to the tail-piece 75 2 by means of the thumb screw 35, the member 32 acting as a lever pivoted on the screw 33 and adjustably positioned by the thumb screw 35. The entire device may be enclosed by means of a cover 39 removably attached to 80 the stationary member 8, or to the bifurcated portions 14 and 15 thereof. For example, the cover 39 may be provided with a lip 40 and a snap portion 41 adapted to engage with the edges of the members 14 and 15. 85

It will be seen that, after the instrument has been properly tuned by operation of pegs 22, the tail-piece 2 will assume a predetermined position between the stationary member 8 and the bridge 4. The block member 25 is then preferably adjusted so that the member 23 assumes a normal position substantially at right angles to the axis of the strings 1. The instrument may then be played in the normal manner. 90

If it is desired to produce a tremolo effect, the member 29 is moved back and forth so that the ring 30 describes an arc, an extension of which would cross the strings 1. This arc follows the normal movement of the hand in playing an instrument of the character described hereinabove. This motion of member 29 imparts an arcuate or vibratory movement to the member 23, as indicated by the arrows, said member 23 being stationary at one end, namely, the end that is held in contact with block 25 and stationary member 8. As a result of this vibrating movement of the member 23, the tail-piece 2 is moved slightly in substantially the plane of the strings 1, so as to alternately increase and decrease the tension of the strings 1. 100

The amplitude of the motion of the tail-piece 2 is very slight and generally less than $\frac{1}{16}$ th of an inch, although the motion of the member 29 at its extreme may be appreciable, namely, 2 to 4 inches. The member 38 resting on the tail-piece 2 pivots at its upper edge in the grooves 37 of lever arm 36, and therefore, does not influence the reciprocating motion of the movable tail-piece 2. 110

In this manner the tension of the vibrating strings 1 is varied during operation of the instrument, the variation being of equal amplitude on each side of the normal position 115 of the tail-piece.

In this manner the frequency of the vibrations from the strings 1 is varied from above to below the normal frequency, the average frequencies or mean frequencies during oper- 120 125

ation of the device being equivalent to normal frequency. The tremulous or wavering effect thus produced does not change the mean frequency of the vibrating strings, but merely causes said strings to change in pitch from normal to above normal, back to normal, and then below normal. A very pleasing and accurate effect is thus obtained which is not obtainable with any of the known devices designed to obtain a similar result.

It is to be understood that although the member 29 as disclosed hereinabove is adapted for manual operation, mechanical means may be provided for vibrating the member 29 on the member 23.

In Figs. 5 and 6 a modified form of construction is shown. The movable tail-piece 2 is here provided with an extension 43 which is connected by means of the tension spring 20 16 with the stationary member 8. The block 25 attached to the stationary member 8 is preferably provided with an aperture 44 adapted to receive a member 23' provided with pointed pins 45 adapted to be rotatably seated or pivoted in the upper and lower portions of block 25 enclosing the aperture 44.

The member 23' may be connected by any suitable means, as for example, a heavy spring member 46, to a suitable actuating means such as the holder 28 and the member 29. The member 23' of the spring member 46 may, therefore, pivot at 45. The member 23' is also preferably connected to the tail-piece 2, a U-shaped member 47 being preferably attached to the longitudinal extension 43 of the tail-piece 2 in any suitable manner and provided with recesses adapted to receive a pin 48 carried by the member 23'. A reciprocated radial motion of the member 23' on the pivot 45 will thus be translated into a reciprocated longitudinal motion of the tail-piece 2 by reason of the connection made between the tail-piece 2 and particularly the U-shaped member 47 with the member 23' by means of the pin 48.

It has been found that an instrument provided with the device described hereinabove maintains its tone or correct pitch for a much longer period of time than an instrument provided with an ordinary stationary tail-piece. The spring 16 apparently equalizes the tension on the strings and takes care of minor variations which may occur due to elongation of the strings. Furthermore, instruments provided with the elastic flexible and movable tail-piece embraced by this invention can be subjected to much greater abuse without breaking the strings. If, for example, one or more of the strings of an instrument of this character are greatly displaced by the operator, they will not break, as the spring 16 gives and thereby the tension or load on the strings is reduced.

Furthermore, instruments provided with this invention are capable of producing a

greater volume of tone, the entire instrument vibrating under the influence of the vibrations of the strings, instead of imparting such vibrations to the head of the instrument only.

The purpose of the lever member 32 is, as has been described before, to increase pressure on the head 5 through the bridge member 4. The lever member 32 is particularly adapted for use on banjos, and other stringed instruments, such as guitars or mandolins do not need this particular portion of the device.

It is to be understood that numerous changes and modifications may be made in the construction of the device, and numerous adaptations and uses may be made thereof without departing from the scope of this invention. The invention broadly relates to a device including a movable tail-piece and the provision of means whereby the tension of strings of an instrument may be increased and decreased alternately, by moving a tail-piece substantially along the axis of the strings and without bending the strings themselves, thereby obviating the tendency for the strings to break. All changes and modifications coming within the scope of the following claims are embraced thereby.

I claim:

1. In a stringed musical instrument, the combination of a tail-piece adapted to anchor vibrating strings, spring means connected to said tail-piece and adapted to maintain the strings under tension, and means for moving said tail-piece so as to alternately increase and decrease the tension of said vibrating strings.

2. In a stringed musical instrument, the combination of a tail-piece adapted to anchor vibrating strings and adapted to be moved in a plane substantially in the plane of said strings, spring means connected to said tail-piece and adapted to maintain the strings under tension, and means for moving said tail-piece so as to alternately increase and decrease the tension of said vibrating strings.

3. In a stringed musical instrument, the combination of a tail-piece adapted to receive and hold ends of vibrating strings, an anchor member, spring means connecting said tail-piece and anchor member and adapted to maintain the strings under tension, and means for moving said tail-piece substantially in the plane of said strings so as to alternately increase and decrease the tension of said vibrating strings.

4. In a device for producing tremolo effects on stringed musical instruments, the combination of a tail-piece adapted to receive and hold the ends of vibrating strings, an anchor member secured to the body of the stringed instrument, spring means connecting said tail-piece and anchor member and adapted to maintain the strings under tension, and

means for moving said tail-piece so as to alternately increase and decrease the tension of said vibrating strings.

5. In a device for producing tremolo effects on stringed musical instruments, the combination of a tail-piece adapted to receive and hold the ends of vibrating strings, an anchor member, spring means connecting said tail-piece and anchor member and adapted to maintain the strings under tension, and means for moving said tail-piece so as to alternately increase and decrease the tension of said vibrating strings, said means including a member substantially transverse to the longitudinal axis of the strings.

6. In a device for producing tremolo effects on stringed musical instruments, the combination of a tail-piece adapted to receive and hold the ends of vibrating strings, an anchor member, spring means connecting said tail-piece and anchor member and adapted to maintain the strings under tension, and means for moving said tail-piece so as to alternately increase and decrease the tension of said vibrating strings, said means including a member pivotally connected to the anchor member at one end and operably connected to the tail-piece and spring.

7. In a device for producing tremolo effects on stringed musical instruments, the combination of a tail-piece adapted to receive and hold the ends of vibrating strings, an anchor member, spring means connecting said tail-piece and anchor member and adapted to maintain the strings under tension, and means for moving said tail-piece so as to alternately increase and decrease the tension of said vibrating strings, said means including a member pivotally connected to the anchor member at one end, and operably connected to the tail-piece and spring and provided at the other end with means for imparting a reciprocating motion thereto.

8. In a device for producing tremolo effects on stringed musical instruments, the combination of a tail-piece adapted to receive and hold the ends of vibrating strings, said tail-piece being movable substantially longitudinally of said strings, means for moving said tail-piece longitudinally of said strings so as to alternately increase and decrease the tension of said strings, an anchor member and spring means between said last named means and anchor member, adapted to maintain the strings under tension.

9. In a device for producing tremolo effects on stringed musical instruments, the combination of a tail-piece adapted to receive and hold the ends of vibrating strings, means for moving said tail-piece substantially longitudinally of the strings so as to alternately increase and decrease the tension of said strings, said means including a member substantially parallel to said strings and movable in an arc extending across said strings,

an anchor member and spring means between said means for moving the tail-piece and anchor member, adapted to maintain the strings under tension.

Signed at Los Angeles, Calif., this 31st 70 day of July, 1929.
